UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

POWDER CONTAINER AND DISPENSER.

1,115,062.

Specification of Letters Patent.

Patented Oct. 27, 1914.

Application filed October 8, 1913. Serial No. 793,999.

To all whom it may concern:

Be it known that I, FRANZ A. FULLER, a citizen of the United States, residing in the city of Newark, in the county of Essex and 5 State of New Jersey, have invented certain new and useful Improvements in Powder Containers and Dispensers, of which the following is a full, clear, and exact description, such as will enable others skilled in the art 10 to which it pertains to make, construct, and use the same, reference being had to the accompanying drawings, and to numerals of reference marked thereon, forming a part of this specification.

15 The invention relates to powder containers and dispensers, and relates more particularly to a device of that type used for carrying and applying toilet powder.

The object of the invention is to provide 20 novel and improved means so as to permit the toilet powder to be readily and instantly applied when desired from time to time, while preventing accidental escape of the powder from the container or case.

25 A further object of the invention is to provide means to freely allow the powder to escape through the powder passage, thereby avoiding any liability of the powder being retarded in its escape through the powder 30 passage by breaking up the powder in the container when the same becomes caked or packed as has heretofore been customary.

With the above and other objects in view, the invention consists in the novel construction, combination and arrangement of parts 35 to be hereinafter fully described, and specifically pointed out in the appended claim.

In the accompanying drawings illustrating my invention, Figure 1 represents a side 40 elevation of my invention, Fig. 2 represents a similar view showing the lid or cover removed, Fig. 3 represents a partial axial section of the device shown in Fig. 1, and Fig. 4 represents a side elevation of the hollow 45 cap with the closure secured thereto.

Similar characters of reference designate corresponding parts throughout all the different figures of the drawings.

In the drawings 1 represents a cylindrical 50 casing or tube, closed at one end and provided at its other end with a removable extension constituting a lid or cover 2. Any convenient form of fastening means such as

for instance a bayonet lock 30 is employed to fasten the casing 1 and lid 2 together. 55

The lid or cover 2 comprises an open-ended tubular sleeve 3, to one end of which is fitted a hollow cap 4, provided with a centrally arranged aperture 5 and two diametrically oppositely-arranged depending 60 upturned lugs or ears 6 for the reception of the end of the coil spring 7.

The closure consists of a tapered head 8 provided with an annular enlargement 9 and an integral hollow extension 10. A breaker 65 11 of any convenient form, the extremity of which is flattened out, as at 12 and provided with an aperture 13 for the reception of the other end of the coil spring 7, is secured in the extension 10 in any convenient manner. 70

It will thus been seen that the closure and the powder breaker are carried by the lid or cover by means of the coil spring 7, and removal of the lid or cover 2 from the casing or tube 1 enables the tube to be filled with 75 powder or the like without affecting the closure, breaker or spring. Downward pressure being applied upon the tube 1 causes the tapered head 8 of the spring pressed closure to be forced away from the aperture 5 in the hollow cap 4, permitting a portion of the contents of the tube to escape, at the same time causing the breaker 11 to break up the caked or packed powder in the casing or tube. 80

The construction of the various parts is 85 of such a nature as to lend themselves to be readily manufactured by the ordinary punches and dies.

Experience has demonstrated that the organization above described is a highly efficient one, and while the device above described is the preferred embodiment of my present invention, I do not care to restrict myself to the exact details of construction, combination and arrangement herein set 90 forth, it being obvious that minor variations thereof not involving the exercise of invention may be made by any skilled mechanic, and such departure from what is herein described and claimed not involving 95 invention, I consider within the scope and terms of my claim.

I claim:

A container for powder, comprising a tube closed at one end and provided at its 100

other end with a lid or cover, said lid or cover comprising an open ended tubular extension, an apertured hollow cap provided with oppositely arranged spring securing lugs secured in one end of said extension, a spring pressed closure located within said lid or cover, one end of which passes through the apertured cap, a powder breaker secured to the other end of said closure and 10 a closing spring located in said cover, one

end of which is secured to the oppositely arranged lugs of the hollow cap and the other end of which is secured to the powder breaker.

This specification signed and witnessed 15 this 22nd day of September, 1913.

FRANZ A. FULLER.
